APPARATUS FOR HEATING AND
HANDLING ASPHALT

William Joseph Miller, Youngstown, Ohio

Application March 30, 1953, Serial No. 345,418

8 Claims. (Cl. 126—343.5)

1

This invention relates to apparatus for heating and handling asphalt and more particularly to apparatus incorporating a liquid heat transferring medium and means for heating the said liquid.

The principal object of the invention is the provision of a combination asphalt storage and heating tank incorporating a built-in heating means for liquefying asphalt in the heating portion of the apparatus.

A further object of the invention is the provision of a combination asphalt storage, heating and circulating apparatus arranged to utilize waste heat from the heating means in maintaining the asphalt in storage in semi-liquid condition.

A still further object of the invention is the provision of an asphalt storage tank incorporating a built-in asphalt liquefying tank and a built-in liquid heating means together with means for circulating the liquid heating medium through the asphalt liquefying tank.

A still further object of the invention is the provision of a combination asphalt storage and heating apparatus incorporating a built-in fluid heater and circulatory system for a liquid heating medium, the entire apparatus being combined in a portable compact unit.

The apparatus for heating and handling asphalt disclosed herein comprises an improvement in the art relating to asphalt storage and heating which has heretofore been carried out in separate and distinct tanks or other containers. As known in the art, asphalt is commonly stored in storage tanks which are provided with heat exchanger coils and through which a heating medium, either fluid or liquid, may be passed to maintain the asphalt in liquid or semi-liquid condition so that it can be pumped from the storage tanks to a point of use.

In asphalt plants asphalt is commonly heated to render it liquid or semi-liquid and transferred to mixing plants where it is heated additionally to render it completely liquid and then mixed with various aggregates in the form of bituminous concrete, etc.

The operation of such asphalt mixing plants has heretofore necessitated the provision of asphalt storage tanks and separate heating tanks and extensive heating means for heating both the storage tanks and heating tanks, it being understood that the heating tanks were generally of considerably smaller volume than the storage tanks.

The present invention combines in one port-

2

able unit a storage tank with a built-in heating tank and a built-in liquid heater together with means for circulating a liquid heating medium from the liquid heater through the asphalt heating tank and through the necessary connections with the asphalt tanks, which connections enable the asphalt to be handled and simultaneously heated.

Those skilled in the art will recognize that heat ordinarily wasted is thus utilized efficiently and economically in that heat escaping from the liquid heater and the asphalt heating tank is utilized in maintaining the asphalt storage tank at a desirable temperature. Additionally, no heat is lost from piping connections heretofore necessary as such piping connections are almost entirely eliminated due to the incorporation of the several elements in one unit.

With the foregoing and other objects in view which will appear as the description proceeds, the invention resides in the combination and arrangement of parts and in the details of construction hereinafter described and claimed, it being the intention to cover all changes and modifications of the example of the invention herein chosen for purposes of the disclosure, which do not constitute departures from the spirit and scope of the invention.

The invention is illustrated in the accompanying drawing, wherein:

Figure 1 is a vertical section taken longitudinally of the apparatus for heating and handling asphalt.

Figure 2 is a front end view, section lines 1—1 indicating the cross section of Figure 1.

Figure 3 is a horizontal cross section taken on line 3—3 of Figure 2.

Figure 4 is a rear end elevation of the apparatus for heating and handling asphalt.

Figure 5 is an enlarged section on line 5—5 of Figure 4.

Figure 6 is a vertical section taken on line 6—6 of Figure 1.

By referring to the drawings and Figures 1, 2 and 3 in particular it will be seen that the apparatus for heating and handling asphalt comprises a base 10 including spaced longitudinally extending side frame members secured to one another adjacent their opposite ends by transverse framing sections 11—11. A cylindrical tank 12 is mounted on the base 10 inwardly from the ends thereof and includes a front wall 13 and a rear wall 14. An access port 15 is formed in the top of the cylindrical tank 12 and is normally closed by a closure 16.

A false bottom 17 is formed in the cylindrical tank 12 and extends longitudinally thereof between the front and rear walls 13 and 14, respectively, and is bowed downwardly transversely of the cylindrical tank 12 and secured at its longitudinal edges to the inner lower sides of the cylindrical tank 12 so that the area above the false bottom 17 is semi-circular and so that the false bottom 17 hangs, in effect, from the sides of the cylindrical tank 12 and is thereby capable of carrying a considerable volume of asphalt thereabove as it forms, in effect, a continuation of the cylindrical walls of the tank 12.

An access opening 18 is provided in the false bottom 17 and is equipped with a closure 19. A control rod 20 extends from the closure 19 upwardly through the access opening 15 and outwardly through the closure 16 so that the closure 19 may be manually manipulated thereby.

It will thus be seen that the cylindrical tank 12 is divided into upper and lower chambers by the false bottom 17 and that means of communication is established between these upper and lower chambers by the access opening 18 and that such means of communication is controlled by the closure 19.

The cylindrical tank 12 has a container 21 positioned therein above the false bottom 17 and adjacent the front wall 13 thereof and partially extending through the front wall 13. The container 21 is preferably obround and has a front wall 22 and a rear wall 23.

The container 21 has a secondary container 24 positioned therein, which secondary container 24 is preferably obround and of a size smaller than the container 21 and is provided in turn with a front wall 25 and a rear wall 26. The secondary container 24 is adapted to receive the products of combustion as directed thereto from an oil burner 27 which is engaged in an opening 28 in the front wall 25 of the secondary container 24. The products of combustion leave the secondary container 24 through an outlet orifice 29 in the front wall 25 of the secondary container 26, which outlet orifice 29 communicates with a vent stack 30.

The secondary container 24 has a transversely positioned hollow baffle 31 therein extending between the opposite side walls of the secondary container 24 to which it is secured and from the front wall 25 to which it is secured to a point near the rear wall 26 and is thereby located between the inlet orifice 28 through which the products of combustion are introduced into the secondary container 24 and the outlet orifice 29 through which they pass from the container 24.

The container 21 is adapted to be filled with a liquid heating medium such as oil as is the hollow baffle 31. Tubular members 32 and 33 communicate with the hollow baffle 31 and the interior of the container 21 so that oil may be circulated therethrough.

Means for circulating the oil comprises a pump 34 driven by a motor 35 which is mounted on a transverse platform 36 across the front of the base 10 and which may comprise the top wall of a fuel supply tank with the oil burner 27, if desired.

The tubular member 32 heretofore referred to communicates directly with the hollow baffle 31 and the lower portion of the container 21 while the tubular member 33 communicates with the hollow baffle 31 and with a manifold 37 which in turn establishes communication with a longitudinally extending oil line 38 most of which is

positioned in the lowermost portion of the chamber beneath the false bottom 17 in the cylindrical tank 12.

The oil line 38 extends completely through the end walls 13 and 14 of the cylindrical tank 12 and does not communicate with either of the chambers above or below the false bottom 17 therein. A tubular member 39 extends from the upper portion of the container 21 to the pump 34 and thence to a hot oil transfer line 40 which like the hot oil line 38 lies in the bottom cylindrical tank 12 below the false bottom 17 and extends through the end walls 13 and 14 thereof.

A heat exchange coil 41 is positioned in the chamber beneath the false bottom 17 and has one end thereof extending out through the rear wall 14 of the cylindrical tank 12 where it communicates by way of a valve 42 with the hot oil line 40, heretofore referred to. The other end of the heat exchange coil 41 also extends through the end wall 14 and communicates by way of a valve 43 with the hot oil line 38.

It will thus be seen that when the pump 34 is operated, oil from the container 21 flows outwardly through the tubular member 39 and through the hot oil line 40 to the valve 42 from whence it flows through the heat exchange coil 41 and serves to liquefy asphalt in the chamber below the false bottom 17. Leaving the heat exchange coil 41, it flows through the valve 43 and into the hot oil line 38 by which it returns to the front of the apparatus and to the manifold 37 and the tubular member 33 which delivers it into the hollow baffle 31.

The oil flows from the hollow baffle 31 to the container 21 through the tubular member 32, heretofore referred to, and thus completes the cycle. It will thus be seen that when the oil burner 27 is operated, hot gaseous products of combustion are delivered into the secondary container 24 which is almost completely surrounded by oil in the container 21 and that such oil is also present in the hollow baffle 31 within the secondary container 24. The oil is, therefore, heated efficiently and rapidly and is circulated by the pump 34 so that asphalt in the lower chamber beneath the false bottom 17 of the cylindrical tank 12 is rapidly liquefied and may be readily pumped therefrom.

Those skilled in the art will also observe that the manifold 37 and the tubular member 33 are provided with valved extensions, the valves being indicated by the numerals 44 and 45 so that hot oil from the apparatus may be circulated through the various bins, tanks, mixers, etc., commonly termed a mixing tower in an asphalt mixing plant.

Additionally, the hot oil is used to maintain desirable temperatures in asphalt handling lines and pump also incorporated in the apparatus and as best shown in Figures 1, 3 and 4 of the drawings.

By referring to Figure 1 of the drawings it will be seen that an asphalt line 46 communicates with the lower rear portion of the chamber beneath the false bottom 17 in the cylindrical tank 12 and extends through the end wall 14 into a jacketed section 46A which in turn communicates with a jacketed three-way valve 47.

A hot oil line 48 controlled by a valve 49 establishes communication between the hot oil line 40 and the jacketed section 46A of the asphalt line 46. The valve 47 is also jacketed as is a strainer 58 and an intermediate section of communicating piping 49. A pump 50 is also jacketed

and communicates with the strainer 48 by way of another section of jacketed piping 51 with a secondary three-way valve 52 which is also jacketed.

The secondary three-way valve 52 communicates with a main asphalt line 53. A jacketed portion 53A lies outside the end wall 14 while the remainder lies within the tank 12 and below the false bottom 17. The jacketed portion 53A communicates with the hot oil line 38 by way of a section of hot oil pipe 54 and a valve 55. Thus, hot oil from the container 24 as circulated by the pump 34 and controlled by the valves 49 and 55 flows through the jacketed three-way valves 47 and 52 and the asphalt strainer 58 and pump 50, the asphalt flowing through these portions of the device thus being kept liquid through the jacketed construction in which the hot oil is circulated. Liquid asphalt is delivered at the front of the apparatus at the front end of the asphalt pipe 53 where it emerges through the front wall 13 of the cylindrical tank 12.

The delivery orifice is best shown in Figure 2 of the drawings and it will be obvious to those skilled in the art that suitable jacketed piping (not shown) conveys the asphalt to the mixing tower of the asphalt plant or the like as desired.

As it is necessary to keep the asphalt liquid, it is customarily circulated and provision is therefore made for the return of the unused asphalt to the apparatus and a delivery portion 56 also on the front wall 15 of the cylindrical tank and immediately below the outlet 53 heretofore referred to.

A tubular member 57 delivers the returning asphalt to the lower chamber below the false bottom 17 in the tank 12.

It will occur to those skilled in the art that the hot oil heater portion of the apparatus may be operated more or less continuously to maintain the asphalt in the storage tank comprising the chamber above the false bottom 17 in semi-liquid condition and that when asphalt in completely liquefied state is necessary, as in the operation of the asphalt plant, the asphalt in the limited area in the chamber beneath the false bottom 17 is readily available for use. As such asphalt is removed, the same is replenished from the supply in storage flowing through the access opening 18, as desired.

It will also be observed by those skilled in the art that the system for heating and circulating the hot oil is separate and distinct from the asphalt handling system as the hot oil pump 34 is driven by the motor 35 while the asphalt pump 50 is driven by a separate motor 58.

A secondary transverse tank 59 forms a platform for the strainer 48 and pump 50 and may obviously be interconnected by way of valves with the hot oil circulating lines and used as a hot oil storage and/or supply tank, if desired.

It will thus be seen that the several objects of the invention are met by the apparatus as herein disclosed and that extremely economical operation is achieved due to the close relationship of the various portions of the apparatus to the end that such heat as is wasted from the liquid heating means is used in maintaining the asphalt storage at desirable temperature.

Having thus described my invention, what I claim is:

1. Apparatus for heating and handling asphalt comprising a primary tank having a false bottom therein dividing said tank into upper and lower chambers, there being an opening through the

false bottom establishing communication between said upper and lower chambers, a secondary tank positioned substantially within said primary tank and above said false bottom thereof, one wall of said secondary tank being common with one wall of said primary tank, a container positioned within said secondary tank and having one wall common with said common wall of said primary tank and said secondary tank, said common wall of said container having inlet and outlet openings for the introduction and removal of products of combustion, means for supporting combustion in said container, said secondary tank surrounding said container in spaced relation thereto and together therewith defining an oil heating chamber surrounding the container and said primary tank comprising an asphalt storage tank, a heat exchanger in said primary tank below said false bottom, and means including a circulating pump establishing communication between said oil heating chamber and said heat exchanger whereby asphalt in the chamber below the false bottom may be rapidly heated and liquefied, and means communicating with said chamber beneath the said false bottom of said primary tank for removing asphalt therefrom.

2. The apparatus for heating and handling asphalt set forth in claim 1 wherein the means for removing asphalt from the chamber beneath the false bottom of the primary tank comprises a secondary pump and communicating piping, said pump and piping being jacketed and the jackets thereof being in communication with said heat exchanger.

3. The apparatus for heating and handling asphalt set forth in claim 1 wherein said container has therein a transversely positioned longitudinally extending hollow baffle positioned between said inlet and outlet openings, and wherein said hollow baffle is in communication with said oil heating chamber.

4. Apparatus for heating and handling asphalt comprising a cylindrical tank having front and rear walls and a concave false bottom extending transversely and arcuately between the opposite sides of said cylindrical tank and engaging the front and rear walls at its ends and having an opening and valve means for controlling said opening and dividing said cylindrical tank into

upper and lower chambers for the reception of asphalt, said cylindrical tank having an access opening in its uppermost portion, means extending from said valve to said access opening for manipulating said valve, a secondary cylindrical tank having front and rear walls and positioned through the front wall of said cylindrical tank and positioned substantially within said cylindrical tank above the false bottom, a cylindrical container having front and rear walls and positioned through front wall of said secondary tank and positioned substantially within said secondary tank in spaced relation to the walls thereof, the area around said container and within said

secondary tank comprising an oil heating chamber, a longitudinally extending transversely positioned baffle in said container, said front wall of said container having inlet and outlet openings respectively below and above said baffle, an oil burner in communication with said inlet opening for supporting combustion in said container and a flue in communication with said outlet opening, a heat exchanger in the first mentioned cylindrical tank below the false bottom thereof and tubular means including a pump connecting said heat

5. The apparatus for heating and handling asphalt set forth in claim 4 wherein the area around said container and within said secondary tank is substantially filled with asphalt.

6. The apparatus for heating and handling asphalt set forth in claim 4 wherein the area around said container and within said secondary tank is substantially filled with asphalt.

7. The apparatus for heating and handling asphalt set forth in claim 4 wherein the area around said container and within said secondary tank is substantially filled with asphalt.

8. The apparatus for heating and handling asphalt set forth in claim 4 wherein the area around said container and within said secondary tank is substantially filled with asphalt.

9. The apparatus for heating and handling asphalt set forth in claim 4 wherein the area around said container and within said secondary tank is substantially filled with asphalt.

10. The apparatus for heating and handling asphalt set forth in claim 4 wherein the area around said container and within said secondary tank is substantially filled with asphalt.

exchanger and said oil heating chamber, and secondary tubular means in communication with the chamber in the cylindrical tank below the false bottom for removing asphalt therefrom.

5. The apparatus for heating and handling asphalt set forth in claim 4 wherein the baffle in said container is hollow and in communication with the said oil heating chamber.

6. The apparatus for heating and handling asphalt set forth in claim 4 wherein the tubular means in communication with the chamber below the false bottom of the cylindrical tank includes a strainer and a pump and wherein said tubular means, strainer and pump are jacketed and the jackets thereof are in communication with said secondary tank so that hot oil may be pumped therethrough to maintain the temperature of asphalt moved therethrough.

7. The apparatus set forth in claim 4 including a unitary mounting frame secured thereto and extending beyond the front and back walls of said cylindrical tank and having a fuel tank mounted adjacent said front wall and forming a support for said oil burner and an oil storage tank mounted adjacent said back wall and forming a support for said asphalt pump and strainer and forming a reservoir for oil to be heated in said apparatus.

8. Apparatus for heating and handling asphalt comprising a primary tank having a false bottom therein dividing said tank into upper and lower chambers, the false bottom having an opening establishing communication between said upper and lower chambers, a secondary tank positioned substantially within said primary tank, one wall 30 of said secondary tank being common with one

wall of said primary tank, a container positioned within said secondary tank and having one wall common with said common wall of said primary and said secondary tank, said common wall of said container having inlet and outlet openings for the introduction and removal of products of combustion, means for supporting combustion in said container, said secondary tank and said container being disposed one within the other in spaced relation to each other and defining an oil heating chamber surrounding the container and said primary tank comprising an asphalt storage tank, a heat exchanger in said primary tank below said false bottom, and means including a circulating pump establishing communication between said oil heating chamber and said heat exchanger whereby asphalt in the chamber below the false bottom may be rapidly heated and liquefied, and means communicating with said chamber beneath the said false bottom of said primary tank for removing asphalt therefrom.
